UNITED STATES PATENT OFFICE.

ARNOLD JOHN NOBLE, OF SUDBURY, ONTARIO, CANADA.

RAIL-JOINT PLATE.

Application filed March 20, 1922. Serial No. 545,332.

To all whom it may concern:

Be it known that I, ARNOLD JOHN NOBLE, a subject of the King of Great Britain, and resident of Sudbury, in the Province of Ontario, Dominion of Canada, have invented 5 certain new and useful Improvements in Rail-Joint Plates, of which the following is a specification.

This invention relates to rail joint plates, 10 and has for its objects to provide a rail joint plate which is so constructed as to afford an anti-slipping means for the rail and angle bar.

Another object is to provide a means of 15 preventing the joint plate from moving in any direction on the ties and the said means are designed to consist of a plurality of checkered ribs angular in cross section formed integral with the under part of the 20 plate and designed under the pressure of the train passing on the rail to become embedded into the ties.

Further objects are to provide a reinforcing member, which is formed integral with 25 the joint plate and designed to extend underneath the same between the two ties. The reinforcing member to be located exactly underneath the joint so as to positively prevent any springing of the butting rail ends, 30 when the trucks of a heavy locomotive are passing on the joint.

Further objects still are to provide a rail joint plate, which is of such a construction 35 as to enable it to be used with the present standard rails and angle bars, thus affording a plate that can be adapted to use at a minimum cost.

Further objects still are to provide a rail joint plate, that is simple in construction, not 40 liable to go out of repair, and generally to adapt the several parts to better perform the functions required of them.

With the above and other objects in view, the invention consists essentially of the improved 45 construction, hereinafter described in detail in the accompanying specification and drawings.

In the drawings:

Figure 1 is a perspective view of a rail joint and angle bars equipped with the improved plate.

Figure 2 is a longitudinal section taken through the plate and showing the rail and angle bars in elevation.

Figure 3 is a cross section taken through the rail and plate.

Figure 4 is a perspective view of the improved rail joint plate.

Figure 5 is a bottom plan view of the 60 same.

Figure 6 is a longitudinal section of the same.

Figure 7 is a cross section on the line 7-7 of Figure 5.

Like characters of reference indicate corresponding parts in all the figures.

Referring to the drawings, A represents a rail joint formed by the butting ends of the two rails 10 and 11 and reinforced by the angle bars 12 and 13, which are of standard construction.

The butting ends of the rails 10 and 11 are designed to be supported on an improved rail joint plate B which consists of a plate 14 having its under face formed integral 75 with the checkered ribs 15, which are triangular in cross section.

The plate is designed to rest on two wooden ties 16 and 17, which are located 80 relatively close to one another in order to provide a space in which is designed to extend a reinforcing member 18 formed integral with the plate 14 and extending underneath the same. The reinforcing member 18 is triangular in cross section and extends 85 crosswise of the plate 14, leaving at its ends a free edge of the plate measuring a few inches, and which is designed to afford a better means of easily tamping the ties.

The apex of the inverted triangular reinforcing member 18 is designed to be in alignment with the butting ends of the rails 10 and 11, so that the joint stands on the strongest point of the plate. One of the longitudinal edges of the plate 14 is formed with 90 shoulders 19 and 20, which are in stepped relation as clearly shown in Figure 4 of the drawings.

The shoulder 20 is designed to afford a suitable stop for the base of the rail, while 100 the shoulder 19 stops the longitudinal edge of the angle bar 13 which rests on the base of the rail.

Two orifices 21 and 22 are formed in the shoulder 20 and designed to register with 105 notches formed in the angle bar 13 in order to engage the spikes 23 used to securely fasten the bar 13 and rail joints to the joint plate 14.

The opposite side of the rail or that on 110 which the angle bar 12 is located is secured to the plate and tie by means of a plurality

of spikes 24 extending through suitable orifices 25 formed at predetermined distances on the plate 14.

The standard angle bars 12 and 13 are secured to the rail web in the usual way through the bolts 26 and the lock nuts 27. When a rail joint is reinforced by means of this improved rail joint plate, the ties 16 and 17 are located at the proper distance 10 from each other, and the plate 14 placed thereon in such a way that the reinforcing member 18 shall be located in the free space between the two ties.

The rail joint is then suitably secured on 15 top of the plate 14 so that the base of the rail abuts the shoulder 20, and the angle bar 13 abuts the shoulder 19 after which the spikes are driven into the ties through their allotted orifices 21, 22 and 25.

20 Obviously the pressure of the train passing on the rails will force the checkered ribs 15 into the ties 16 and 17 and after the former have become embedded in the ties, the plate will be retained against any movement 25 whatever through the stress applied to the rails by the passing trucks of the locomotive and coaches.

It will be seen that by the use of this improved rail joint plate all the standard 30 rails and angle bars at present in use can be retained and to suit the several sizes of rails used, the plates 14 would be made of several standard sizes and the orifices 21, 22 and 25 adapted to receive the spikes 23 and 24 35 would only be drilled through afterwards and according to the size of rails that the plates are to be used with.

As many changes could be made in the above construction, and many apparently 40 widely different embodiments of my invention, within the scope of the claims, con-

structed without departing from the spirit or scope thereof, it is intended that all matter contained in the accompanying specification and drawings shall be interpreted as 45 illustrative and not in a limiting sense.

It will be seen that the rail joint plate is effective to prevent the breaking of the rails at the joint, the breaking of the angle bars and to prevent the joints from spreading. It will further assist in preventing creeping of the track and will considerably strengthen the joint.

What I claim as my invention is:

1. A rail joint plate in combination with 55 rails and angle bars comprising a plate formed with stepped shoulders, designed to abut the rail bases and one angle bar, a reinforcing member underneath the plate formed integral therewith, the lower face 60 of the plate being formed with checkered ribs, designed to engage the ties, and means engaging the bars and plate to secure the same to the ties.

2. A rail joint plate in combination with 65 rails and angle bars comprising a plate formed with stepped shoulders designed to abut the rail bases and one angle bar, a reinforcing member underneath the plate formed integral therewith, and triangular 70 in cross section, the lower face of the plate being formed with checkered ribs designed to engage the ties and means engaging the bars and plate to secure the same on the ties.

In witness whereof I have hereunto set my hand in the presence of two witnesses.

ARNOLD JOHN NOBLE.

Witnesses:

E. GRINON,
LOUIS LUCIAN.
